UNITED STATES PATENT OFFICE.

JONATHAN J. MOORE, OF THORNTOWN, INDIANA.

STEAM-BOILER.

SPECIFICATION forming part of Letters Patent No. 393,781, dated December 4, 1888.

Application filed June 11, 1888. Serial No. 276,678. (No model.)

To all whom it may concern:

Be it known that I, JONATHAN J. MOORE, a citizen of the United States, residing at Thorntown, in the county of Boone and State of Indiana, have invented a new and useful Improvement in Steam-Boilers, of which the following is a specification.

My invention relates to an improvement in steam-boilers of that class which have an internal fire-box.

The object of my improvement is to provide a grate for the fire-box in this class of steam-boilers which shall also form a part of the steam-generating surface.

15 The accompanying drawings illustrate my invention.

Figure 1 represents a longitudinal section of a locomotive or portable boiler having my improvement. Fig. 2 is a plan of the same 20 at *a*, Fig. 1.

My improvement consists in forming a part of the bottom of the fire-box of a solid inclined surface formed by bending the back sheet of the fire-box forward and downward, 25 and in forming the grate of tubes having their open ends inserted in the back sheet of the fire-box, the said tubes being arranged in the same horizontal plane, with open spaces between them, so as to form a grate-surface, 30 whereby the fuel-support consists of a smooth inclined surface from which the coals and ashes will slide forward and a grate formed by the tubes and which forms a part of the water-space of the boiler, all as hereinafter 35 fully described.

In the drawings, *A* is the fire-box.
B is the back sheet of the fire-box, which is

bent forward at a sharp angle, as at *c*, immediately above the point where the tubular grate-bars *D* are inserted, thus forming a partial support for the fuel. The closed ends *e* of the tubes *D* extend nearly to the front wall of the fire-box, but are not secured thereto, the purpose being to avoid any pressure on the walls of the fire-box from the expansion 40 of the grate-bars. For greater security the forward ends of the bars *D* may rest on a cross-bar, *f*, secured to the side walls of the fire-box. The open ends of the tubes *D* are screwed into the back sheet of the fire-box, so 45 that their interiors communicate with and form a part of the water-space which surrounds the fire-box. By this construction all warping and twisting and burning of the grate-bars is 50 avoided. A large proportion of heat which has heretofore been lost in the ash-pit is absorbed by the tubular grate-bars and the inclined portion of the back sheet which forms an extension of the grate and is utilized in the production of steam. 55

I claim as my invention—

In a steam-boiler, the combination of an internal fire-box having its back sheet inclined forward and downward and a series of tubes each having one end inserted in said back 60 sheet of the fire-box below said inclined portion and arranged to form a grate for the fire-box, all substantially as and for the purpose specified.

JONATHAN J. MOORE.
